(57) **CLAIM**

The ornamental design for a carving board, as shown and described.

DESCRIPTION

FIG. 1 is a top/right side perspective view of the carving board design.

FIG. 2 is a top side view of the carving board design.

FIG. 3 is a bottom side view of the carving board design.

FIG. 4 is a left side view of the carving board design.

FIG. 5 is a right side view of the carving board design.

FIG. 6 is a front side view of the carving board design.

FIG. 7 is a rear side view of the carving board design; and,

FIG. 8 is a bottom/right side perspective view of the carving board design.

The broken lines shown in FIGS. 3-8 represent portions of the carving board that form no part of the claim.

1 Claim, 6 Drawing Sheets(56)
